DESIGN FOR A CAMERA CASING

Lew W. Lessler, Johnson City, N. Y., assignor, by mesne assignments, to General Aniline & Film Corporation, New York, N. Y., a corporation of Delaware

Application July 22, 1939, Serial No. 86,191

Term of patent 14 years

To all whom it may concern:

Be it known that I, Lew W. Lessler, a citizen of the United States, residing at 16 Mildred Avenue, Johnson City, in the county of Broome and State of New York, have invented a new, original, and ornamental Design for Camera Casings, of which the following is a specification, reference being had to the accompanying drawing, forming a part thereof.

I claim:

The ornamental design for a camera casing, substantially as shown.

LEW W. LESSLER.
